UNITED STATES PATENT OFFICE.

HARRY WAYTE, OF KALAMAZOO, MICHIGAN, ASSIGNOR OF ONE-HALF TO HERMAN GUMBINSKY, OF KALAMAZOO, MICHIGAN.

SPARK PLUG.

Application filed June 17, 1921. Serial No. 478,307.

To all whom it may concern:

Be it known that I, HARRY WAYTE, a citizen of the United States, residing in the city and county of Kalamazoo, State of Michigan, have invented certain new and useful Improvements in Spark Plugs, of which the following is a specification.

This invention relates to improvements in spark plugs.

10 The main objects of this invention are:

First, to provide an improved spark plug which can be cleaned without removing from the cylinder.

15 Second, to provide an improved spark plug having this advantage in which the electrodes are stationary.

Third, to provide a spark plug having these advantages which is very durable and is not expensive to manufacture.

20 Further objects and objects relating to structural details, will definitely appear from the detailed description to follow.

I accomplish the objects of my invention by the devices and means described in the 25 following specification. The invention is clearly defined and pointed out in the claims.

A structure which is a preferred embodiment of my invention is clearly illustrated 30 in the accompanying drawings, forming a part of this application in which:

Fig. I is a side view of an engine equipped with spark plugs embodying my improvements, the engine being shown conventionally.

35 Fig. II is a side elevation of one of my improved spark plugs.

Fig. III is a detail view mainly in vertical section on a line corresponding to line 40 3—3 of Fig. 4.

Fig. IV is a horizontal section on a line corresponding to line 4—4 of Figs. II and III.

45 In the drawings, similar reference characters refer to similar parts throughout the several views, and the sectional views are taken looking in the direction of the little arrows at the ends of the section lines.

Referring to the drawings, 1 represents an 50 engine. My improved spark plug comprises a tubular body or shell 2 having an internal core seat 3 at its outer end for the insulating core 4. The core 4 has an annular shoulder 5 coating with the seat 3, a packing 6 being 55 preferably provided for the seat.

The body 2 is provided at its inner end with an internal flange 7 providing a restricted opening 8. The end of the body is recessed at 9. The body is provided with an annular external flange 10 providing a seat 60 for the collar 11 carrying the discharge conduit 12. The body has radial passages 13 disposed between its said external and internal seats, while the collar is provided with an annular groove-like passage 14 registering with the radial passages 13. The core 4 is supported with its inner end spaced from but adjacent to the restricted opening 7. The electrode 15 is supported by the core with its tip centrally located in the restricted 65 opening 7. The coacting grounded electrode 16 is mounted on the body with its tip within the recess 8, that is, it extends across the opening so that both electrodes are cleaned by the air and gases rushing 70 through the opening.

The conduit 12 is provided with an inwardly seating check valve 17 and with a manually controlled valve 18. The collar 11 is clamped upon its seat by means of the 80 nut 19 threaded upon the body. This permits of adjustment of the collar to bring the valve levers 20 into the desired operating relation, permitting them being connected to the operating rod 21, so that all of the 85 valves may be opened at the same time. With this arrangement when the valves 18 are opened, the air on the compression stroke and the gases on the explosion stroke are forced through the restricted openings of 90 the plugs and past the electrodes effectively cleaning the same. The check valve prevents entrance of air on the charge stroke. My improved spark plug may be kept clean by occasionally opening the valve 18. 95

I have illustrated and described my improvements in the embodiment which I find very satisfactory, I have not attempted to illustrate or describe certain modifications and adaptations which I contemplate, as I 100 believe the disclosures made will enable those skilled in the art to which my invention relates to embody or adapt the same as may be desired.

Having thus described my invention, what I claim as new and desire to secure by Letters Patent, is:—

1. In a spark plug, the combination of a tubular body having an internal core seat at its outer end and an internal flange at its 110

tip providing a restricted central opening, the inner end of said body being recessed, said body having an external flange below said core seat and radial passages located between said internal and external seats, an insulating core disposed upon said core seat with its inner end adjacent to said restricted opening at the inner end of said body, an insulated electrode supported by said core with its tip centrally of said restricted opening, an electrode mounted on said body with its tip disposed centrally in said recess thereof, a collar mounted on said external seat and provided with a discharge conduit and with an annular groove opening thereto and registering with said radial passages, a manually controlled valve for said discharge conduit and an inwardly seating check valve therefor disposed at the inner side of said manually controlled valve, and a clamping nut for said collar threaded upon said body whereby the collar may be adjusted to position the manually controlled valve.

2. In a spark plug, the combination of a tubular body having an internal core seat at its outer end and an internal flange at its tip providing a restricted central opening, said body having an external flange below said core seat and radial passages located between said internal and external seats, an insulating core disposed upon said core seat with its inner end adjacent to said restricted opening at the inner end of said body, an electrode supported by said core with its tip centrally of said restricted opening, a collar mounted on said external seat and provided with a discharge conduit and with an annular groove opening thereto and registering with said radial passages, a manually controlled valve for said discharge conduit and an inwardly seating check valve therefor disposed at the inner side of said manually controlled valve, and a clamping nut for said collar threaded upon said body whereby the collar may be adjusted to position the manually controlled valve.

3. In a spark plug, the combination of a tubular body having an internal core seat at its outer end and an internal flange at its tip providing a restricted central opening, said body having an external flange below said core seat and radial passages located between said internal and external seats, an insulating core disposed upon said core seat with its inner end adjacent to said restricted opening at the inner end of said body, an electrode supported by said core with its tip centrally of said restricted opening, a collar mounted on said external seat and provided with a discharge conduit and with an annular groove opening thereto and registering with said radial passages, a manually controlled valve for said discharge conduit and an inwardly seating check valve therefor disposed at the inner side of said manually controlled valve, and a clamping nut for said collar threaded upon said body whereby the collar may be adjusted to position the manually controlled valve.

4. In a spark plug, the combination of a tubular body having an internal core seat at its outer end and an internal flange at its tip providing a restricted central opening, said body having an external flange below said core seat and radial passages located between said internal and external seats, an insulating core disposed upon said core seat with its inner end adjacent to said restricted opening at the inner end of said body, an electrode supported by said core with its tip centrally of said restricted opening, a collar mounted on said external seat and provided with a discharge conduit and with an annular groove opening thereto and registering with said radial passages, a manually controlled valve for said discharge conduit and an inwardly seating check valve therefor disposed at the inner side of said manually controlled valve, and a clamping nut for said collar threaded upon said body whereby the collar may be adjusted to position the manually controlled valve.

therefor disposed at the inner side of said manually controlled valve, and a clamping nut for said collar threaded upon said body 45 whereby the collar may be adjusted to position the manually controlled valve.

3. In a spark plug, the combination of a tubular body having a restricted opening at its inner end and an external seat and radial passages above said seat, an insulating core, an electrode supported by said core with its tip within said restricted opening, a coating electrode disposed adjacent said opening, a collar mounted on said external seat and provided with a discharge conduit and with an annular groove opening thereto and registering with said radial passages, a manually controlled valve for said discharge conduit and an inwardly seating 60 check valve therefor disposed at the inner side of said manually controlled valve, and a clamping nut for said collar threaded upon said body whereby the collar may be adjusted to position the manually controlled 65 valve.

4. In a spark plug, the combination of a tubular body having an external seat and radial passages above said seat, an insulating core, an electrode supported by said core, 70 a collar mounted on said external seat and provided with a discharge conduit and with an annular groove opening thereto and registering with said radial passages, a manually controlled valve for said discharge conduit and an inwardly seating check valve therefor disposed at the inner side of said manually controlled valve, and a clamping nut for said collar threaded upon said body whereby the collar may be adjusted to position the manually controlled 75 valve.

In witness whereof I have hereunto set my hand and seal.

HARRY WAYTE. [L.S.]
